(57) **CLAIM**

The ornamental design for a cigarette pack, as shown and described.

DESCRIPTION

FIG. 1 is a perspective view of a cigarette pack showing our design;

FIG. 2 is a perspective view of our cigarette pack with the lid open;

FIG. 3 is a front view thereof;

FIG. 4 is a left side view thereof;

FIG. 5 is a rear view thereof; and,

FIG. 6 is a bottom view thereof.

It is understood that the right side view is a mirror image of the left side view. The broken lines are for illustrative purposes only and forms no part of the claimed design.
